BED HEADBOARD OR THE LIKE

Richard M. Chapin, Charlotte, N.C., assignor to C. B. Atkin Company, Knoxville, Tenn., a corporation of Tennessee

Filed Oct. 14, 1968, Ser. No. 13,983

Term of patent 3½ years

Int. Cl. D6—01

U.S. Cl. D5—4

The back of the bed headboard is substantially plain and unornamented.

The dominant features of my design reside in those portions shown in full lines, the conventional lower portions being shown in broken lines in FIGURE 1 and shown partially broke away for convenience of illustration.

I claim:

The ornamental design for a bed headboard or the like, substantially as shown and described.
